UNITED STATES PATENT OFFICE

2,664,487

ELECTRICAL RESISTOR

Henry C. Gorden, Los Angeles, Calif., assignor to
 Gorman Manufacturing Corporation, Los Angeles, Calif., a corporation of California

Application January 7, 1952, Serial No. 265,249

9 Claims. (Cl. 201—67)

1

This invention relates to an electrical resistance device for determining the amount of current flowing in a circuit for any given voltage applied to the circuit and has as its primary object the provision of a precision resistor of the type embodying an electrically conductive coil wound on a spool and encased in a housing which spool and housing are formed of an electrically insulating material; the invention residing in a construction and arrangement of parts and in a mode of assemblage whereby the device may be readily and economically manufactured and whereby a resistor will be produced that is characterized by its compactness and lightness and its affording a maximum amount of performance with the smallest amount of weight and size, by its capability of withstanding great thermal change from hot to cold and vice versa, and by its immunity to the deteriorating effects of long exposure to adverse climatic conditions.

Another object is to provide a construction in the resistor which is particularly applicable to and facilitates the production of resistors of extremely small caliber particularly suitable for use in electronic systems such as sets used in radio and radar and television equipment and the like.

Another object is to provide a construction for facilitating the positioning of a resistance coil on a spool together with laterally extending rigid terminals at the ends of the coil, arranging the assembly within a cylindrical shell and effectively sealing the coil within the shell.

Another object is to provide a wire-wound precision resistor of the above character which when constructed of extremely small or minute size will be quite strong and accordingly not subject to easy breakage and damage as is the case with the fragile small resistors now generally on the market, and which with the characteristics above set forth is rendered especially applicable for use in aircraft, air-borne missiles and equipment calling for maximum resistor performance under extreme variations in altitude ranging up to tremendous heights, as well as extreme variations in temperature as for example from minus 70° centigrade to plus 200° centigrade, and where extreme lightness in weight and small dimension is a desideratum.

A further object is to provide a construction in a resistor of the type specified whereby the terminals of the resistor coil may be either from the side or from the ends of the device according to requirements and to facilitate application of the resistor in a particular piece of equipment.

With the foregoing objects in view together

2

with such other objects and advantages as may subsequently appear, the invention resides in the parts and in the combination, construction and arrangement of parts hereinafter described and claimed, and illustrated by way of example in the accompanying drawing in which:

Fig. 1 is a perspective view of a preferential form of the resistor;

Fig. 2 is a view in longitudinal section and partly in elevation of the resistor shown in Fig. 1;

Fig. 3 is a perspective view of the resistor spool and coil assembly as removed from its housing or shell;

Fig. 4 is a view in longitudinal section of the assembly shown in Fig. 3;

Fig. 5 is a perspective view with portions broken away of a shell for receiving the assembly shown in Figs. 3 and 4 for encompassing and housing the resistor coil;

Fig. 6 is a view in section and elevation illustrating the manner of assembling the coil assembly in Figs. 3 and 4 within the shell depicted in Fig. 5;

Fig. 7 is a view illustrating the parts of the spool and coil assembly as separated;

Fig. 8 is a view in longitudinal section illustrating a modified form of the spool and coil assembly;

Fig. 9 is a view in vertical section showing another form of the invention;

Fig. 10 is a view in side elevation depicting a further form of the invention;

Fig. 11 is a view in horizontal section taken on the line 11—11 of Fig. 10, with the coil removed; and

Fig. 12 is a view in vertical section and elevation taken on the line 12—12 of Fig. 11.

Referring to the drawing more specifically A indicates a cylindrical shell which is open at least at one of its ends and is provided at an end thereof with a wall 10 having an axial circular opening 11 which wall may be formed integral with the shell A as shown in Figs. 1, 2, 5, and 6 or may be formed independent of the shell and subsequently applied thereto to close one end thereof as shown in Figs. 9, 10 and 11.

In the construction shown in Figs. 1, 2, 5, 6 and 10 the cylindrical shell A is formed with a slot 12 adjacent its forward or open end and with a slot 14 adjacent its other end closed by the wall 10.

The shell A is designed to receive a spool and coil assembly B particularly shown in Figs. 3 and 4 which assembly embodies a tubular cylindrical core 15 and which core is insertable in the open

end of the shell A with the inner free end portion thereof inserted in the opening 11 and snugly engaged with the portion of the end wall 10 surrounding said opening as shown in Figs. 2, 9 and 11.

An annular flange 16 is formed on the outer end of the cylindrical core 15, the marginal portion of which is formed to abut the outer open end of the shell A and being formed with a reduced inner marginal portion 17 dimensioned to 10 snugly abut the inner peripheral portion of the shell A adjacent the outer end thereof.

The shell A with its end wall 10 and also the spool comprising the core 15 with its end flange 16, are formed of suitable insulating material 15 such for example as a plastic composition composed of a phenolic thermo-setting compound, a cellulose product, a phenol resin product, "nylon," pressed fibers, rubber and the like; being preferably molded of a non-hygroscopic heat resistant compound, with high dielectric strength and very low coefficient of expansion and highly resistant to thermal shock; the compound most suitably employed being one that can withstand over 200° centigrade and at least minus 70° centigrade.

A resistance coil composed of a suitable wire formed of an electrical conductive material of suitable resistance quality such as nichrome wire, is wound into a cylindrical coil C comprising a requisite number of convolutions imposed on the core 15. This coil C may either be wound directly on the core 15 or may be wound on a suitable arbor and thereafter telescoped on the core. The terminals a—b of the wire forming cylindrical coil C may be threaded through openings 18 and 19 in the core 15 as shown in Fig. 8, or may be directed through the slots 12 and 14 in the shell A when assembling the element B therein, but the present invention contemplates the employment of a more substantial construction, which in the construction shown in Figs. 1 to 7 inclusive consists in providing the device with a pair of rigid electrically conductive terminal posts D—E which project through the slots 12—14; the post D being formed on the margin of an annulus 20 encircling the core 15 between the flange 16 and the adjacent end of the coil C to which one end a of the wire forming the coil C is affixed in suitable fashion, preferably by welding. The post E is formed on the margin of an annulus 21 encircling the inner end portion of the core 15 and to which the other terminal b of the wire forming coil C is affixed as by welding. In connecting the ends a—b of the coiled wire to the annuli 20—21 strain loops 22—23 are formed in such ends between their point of attachment to the annuli and the ends of the coil C.

Suitable insulating gaskets 24 and 25 are provided to overlie the inner faces of the annular members 20 and 21 and the end faces of the cylindrical coil C.

In the construction and assemblage of the resistor as shown in Figs. 1 to 7 the spool and coil assembly B is made as shown in Fig. 4; the annulus 20 being first positioned on the core 15 to abut the flange 16 with the gasket 24 abutting and covering the inner face of the annulus 20. The coil C is then provided on the core 15 with one end portion of the resistance wire thereof slightly extended from the coil and formed into the strain loop 22 the outer end of which is affixed to the annulus 20 as before stated. The other end portion of the resistance wire of the

coil C is then formed into the strain loop 23 which is then welded to the annulus 21 which annulus is then positioned on the free end portion of the core 15 in loose relation to the core 5 and coil with the gasket 25 interposed between the annulus 21 and the adjacent end of the coil C. The assembly B and shell A are then put together by inserting the core and coil in the open end of the shell A as shown in full lines in Fig. 6 with the outer end of the post E presented to the slot 14. The core and coil are then advanced into the shell with the outer end portion of the post E passing through the slot 14, as indicated in dotted lines in Fig. 6; the core and shell being thus advanced until the free end of the core 15 is moved into the opening 11 and disposed in close abutting contact with the marginal portion of the end wall 10 surrounding the opening 11 and with the annulus 21 abutting 20 the end wall 10 and with the coil cylinder C abutting the gasket 24 as indicated in broken lines in Fig. 6. The flange 16 will then be disposed in its engaged position with the shell A and with the post D arranged in the slot 12. 25 The posts D and E will then project radially from the shell A to afford connections for electrical conductors with which the resistor is to be associated.

Where the assembly B is formed as shown in 30 Fig. 8, that is without the radial posts D and E and with the terminals a and b of the coil C leading from the ends of the core 15, the shell A is applied over the assembly and disposed with its open end engaged with the flange 16 and 35 with the outer free end of the core 15 extending into the opening 11 and engaged with the end wall 10.

In the arrangements shown in Fig. 9 and in Figs. 10-12 the end wall 10 is formed apart from the cylindrical shell A as a separate piece and is formed to extend into the shell in close telescoped engagement therewith; the end wall 10 in this instance being applied after the assembly B has been disposed within the shell A with the flange 16 engaged with the latter so that in applying the free end wall 10 the outer end of the core 15 will be received in the opening 11 and engaged with the wall 10.

In the construction shown in Fig. 9 the resistor is provided with copper wire terminals 26—26 which lead into the open ends of the core 15 and through openings 18'—19' in the core and have flattened ends 28—28 to which the terminals of the wire coil C are attached by weld joints c. Metal grommets 29—29 are fitted in the ends of the core and have holes 30—30 through which the terminals 26—26 extend, which terminals are anchored in the grommets by solder plugs 31—31 applied in a molten state in the open outer end of the grommets against fiber plugs 31'—31' after completing the assembly. The plugs 31—31 also serve to seal the holes 30—30 leading to the openings 18'—19' thus sealing the latter.

In the construction shown in Figs. 10-12 wherein the end wall 10 is assembled on the shell A, the inner face of the wall 10 as well as that of the flange 16, is formed with an annular recess 32 in which the annuli 21 and 20 are seated and arranged with the terminals E and D thereon extended radially from the end wall and flange through the slots 12 and 14 of the shell.

The free end wall 10, like the flange 16 form closures for the ends of the cylindrical shell A and are snugly fitted to the latter as is the con-

nection between the core and the end wall 10, and if desired the joints between the parts may be sealed by a suitable adhesive. The slots 12-14, and openings 18-19 and 18'-19' are sealed around the terminals extending therethrough.

I claim:

1. An electrical resistor comprising a cylindrical shell open at one end and having an end wall at its other end formed with an axial circular opening, a spool embodying a resistance coil receiving core insertable in the open end of said shell with an end thereof inserted in said opening in snug engagement with the portion of said end wall surrounding said opening, an integral annular flange on the other end of said core abutting the open end of said shell and having a reduced inner marginal portion abutting the inner peripheral portion of said shell adjacent the open end thereof, a cylindrical coil of resistance wire encompassing said core, and terminals on said coil leading exteriorly of said shell.

2. An electrical resistor comprising a cylindrical shell open at one end and having an end wall at its other end formed with an axial circular opening, said shell being formed with a slot adjacent each end thereof, a spool embodying a cylindrical core having a free end and formed with an integral annular flange at its other end, a cylindrical coil of resistance wire encompassing said core having terminals leading from said coil; said spool and coil being arranged within said shell with said flange tightly abutting the open end of the shell and with the free end of said core extending into said end wall opening in snug engagement with the portion of the end wall surrounding said opening, and with said terminals extending through the slots in said shell.

3. The structure called for in claim 2 in which the terminals each comprise a rigid electrically conductive annulus encircling the core adjacent an end of the coil and connected to the latter and a post on and leading from said annulus and extending from the latter through one of the slots in said shell and projecting from the latter.

4. An electrical resistor comprising a cylindrical shell having an open end and a closed end with said closed end formed with an axial circular opening, said shell having a slot adjacent each end thereof, a spool embodying a cylindrical core having a flanged end and a free end, a metallic annulus encompassing each of the ends of said core, a post on each annulus projecting through one of the slots in said shell, a coil of resistance wire encompassing said core having ends one of which is electrically connected to one annulus and the other of which is electrically connected to the other annulus; said core being arranged within said shell with its flanged end

engaging the open end of said shell and with its free end engaged with the opening in the shell end wall.

5. The structure called for in claim 4 in which said shell and spool are formed of a non-hygroscopic heat resistant material with high dielectric strength and very low coefficient of expansion and highly resistant to thermal shock.

10 6. The structure called for in claim 4 in which the resistance wire comprises nicrome wire and in which the ends of said wire are connected to their respective annulus through a strain loop and by a weld joint.

7. An electrical resistor comprising a cylindrical shell having open ends, an end wall closing one end of said shell formed with an axial circular opening, a spool and coil assembly in said shell comprising a tubular core having open ends and formed with a flange on one of its ends 15 seated on and engaging one end of said cylindrical shell, said core having a free end extending into the opening in said end wall and snugly engaged by the latter, and a coil of resistance wire encompassing said core having terminals, 20 said terminals extending through said core and out the open ends thereof.

8. The structure called for in claim 7 together with metal grommets which are inserted in the open ends of the core through which the terminals lead, and solder plugs in said grommets anchoring the terminals therein.

9. An electrical resistor comprising a cylindrical shell, an end wall closing one end of said shell and provided with an axial opening, a spool and coil assembly in said shell comprising a tubular core having open ends and a flange on one of its ends seated on and engaging the other end of said cylindrical shell for closure thereof, the other end of said core being free and extending 35 into the opening in said end wall and snugly engaged by the latter, a coil of resistance wire encompassing said core having terminals, said terminals embodying annuli inset in said flange and end wall and posts extending from the annuli through said shell and projecting therefrom, and insulation gaskets interposed between said annuli and the ends of said coil.

HENRY C. GORDEN.
